(57) **CLAIM**

The ornamental design for a box with ribbon, as shown and described.

DESCRIPTION

FIG. 1 is a front perspective view of a box with ribbon according to the present invention;

FIG. 2 is a first side view thereof;

FIG. 3 is a second view thereof; and,

FIG. 4 is a top view thereof.

The broken line showing of a ribbon represents environment and forms no part of the claimed design.
